US0D1018457S

(12) **United States Design Patent** (10) **Patent No.:** **US D1,018,457 S**
(45) **Date of Patent:** **** Mar. 19, 2024**

(54) **CHARGING STATION**

(71) Applicant: **Shenzhen taiyou Culture Technology Co., LTD**, Shenzhen (CN)

(72) Inventor: **Renlin Sun**, Shenzhen (CN)

(73) Assignee: **Shenzhen taiyou Culture Technology Co., LTD**, Shenzhen (CN)

(**) Term: **15 Years**

(21) Appl. No.: **29/875,048**

(22) Filed: **Apr. 28, 2023**

(51) LOC (14) Cl. **13-02**

(52) U.S. Cl.

(57) **CLAIM**

The ornamental design for a charging station, as shown and described.

DESCRIPTION

FIG. 1 is the usage state diagram of a charging station, showing my new design;

FIG. 2 is another usage state diagram;

FIG. 3 is a top perspective view thereof;

FIG. 4 is a bottom perspective view thereof;

FIG. 5 is a top view thereof;

FIG. 6 is a bottom view thereof;

FIG. 7 is a front view thereof;

FIG. 8 is a rear view thereof;

FIG. 9 is a right side view thereof; and,

FIG. 10 is a left side view thereof.

The broken lines in the drawings illustrate portions of the charging station that form no part of the claimed design.

1 Claim, 10 Drawing Sheets
